United States Patent Office

Des. 218,956
Patented Oct. 13, 1970

218,956

TOWEL OR SIMILAR ARTICLE

Joyce E. Haney, Post, Tex., assignor to Cannon Mills Company, Kannapolis, N.C., a corporation of North Carolina

Original design application Nov. 25, 1968, Ser. No. 14,635, now Patent No. 216,416, dated Dec. 30, 1969. Divided and this application Nov. 20, 1970, Ser. No. 20,188

Term of patent 14 years

Int. Cl. D6—09

U.S. Cl. D92—26

The figure is a top plan view of a towel or similar article, showing my new design.

This is a division of design application Ser. No. 14,635, filed Nov. 25, 1968, now Pat. No. D. 216,416.

I claim:

The ornamental design for a towel or similar article, substantially as shown and described.
